UNITED STATES PATENT OFFICE

2,482,448

RAIN ALARM

Edward H. Wiest, Sr., Indianapolis, Ind.

Application December 10, 1946, Serial No. 715,268

2 Claims. (Cl. 200—52)

1

This invention relates to improvements in rain alarms.

An object of the invention is to provide an improved rain alarm or switch mechanism whose contacts will be held in open position by means of a frangible and replaceable trigger strip which will act to close the contacts of said switch mechanism when rain water falls upon the trigger strip causing the same to break.

Another object of the invention is to provide an improved frangible trigger strip having reinforced ends adapted to be associated with any desired form of mechanical or electrical signal device for normally holding the said mechanism inoperative until the trigger strip is weakened and broken by being moistened by rain water.

Another object of the invention is to provide an improved rain alarm or switch mechanism which will include a resiliently tensioned contact bar adapted to be held in open circuit position by means of removable trigger strips secured at the opposite ends of the switch housing to overlie said contact bar, said trigger strip being breakable when wet by rain water thereby permitting the switch mechanism to operate a signal or alarm.

A further object of the invention is to provide an improved frangible trigger strip held switch mechanism which will be highly efficient in operation, and relatively inexpensive to manufacture and produce.

Other objects will appear as the description proceeds.

In the accompanying drawings which form a part of this application,

Figure 1 is a perspective view of the improved rain alarm or frangible trigger strip operable switch mechanism;

Figure 2 is a longitudinal sectional view through the improved device;

Figure 3 is a view taken on the line 3—3 of Figure 2;

Figure 4 is a sectional view taken on the line 4—4 of Figure 2, and

Figure 5 is a perspective view of a frangible trigger strip.

Like characters of reference are used throughout the following specification and the accompanying drawings to designate corresponding parts.

In carrying out the invention, there is provided a suitable housing generally designated by the reference numeral 1, being of substantially rectangular shape and provided with a

2

bottom 2 removably attached to the housing 1 by means of the screws 3.

A switch 4 is suitably supported in the housing 1 and includes the upwardly extending operator rod 5 which extends upwardly through an opening 6 in the top of the housing 1, and is provided with a peripheral flange 7 upon which the coil spring 8 is seated. A collar 9 of insulating material is disposed concentrically about the opening 6 and is suitably attached to the upper surface of the top of the housing 1. A slideable cap member 10 of insulating material is disposed about the upper end of the collar 9 and is formed with a reduced seat 11 in its upper end for receiving the upper end of the coil spring 8. A bridge member or extension 12 is integrally formed with the cap member 10 and extends upwardly therefrom. The switch 4 is normally closed when the operator rod 5 is in its raised position, but is adapted to be held open when forced downwardly and a thin frangible paper trigger strip 13 is secured tightly across the top of the bridge 12 and made fast at the ends of the housing 1.

An electric buzzer or other desired signal device as generally denoted by the reference numeral 14 is suitably supported in the housing 1 and is connected by means of the electric conductor wires 15 in series with the switch 4 and with a source of electric current supply (not shown).

The frangible trigger strips 13 are formed of thin strips of tissue paper with their opposite ends thickened or reinforced at 16 to be pierced by the outwardly extending pins 17 and 18 extending through the end walls of the housing 1.

Spaced ears 19 and 20 are formed on each end of the housing 1 and are connected by the hinge pins 21 upon which the trigger strip securing plates 22 are pivotally mounted, the same being apertured or formed with sockets 23 for receiving the ends of the pins 17 and 18 when the keeper plates 22 are turned to lie in parallel relation with the ends of the housing 1. Springs 24 will be provided for resiliently holding the keeper plates 22 in closed position when a trigger strip 13 is in place holding the switch 4 in open circuit position.

In operation, the cap member 10 will be depressed to force the contacts of the switch open, and a trigger strip 13 is placed on one pin 17 and secured by turning the keeper plate 22 upwardly, then the strip 13 is extended over the upper surface of the bridge 12 while depressed and its

opposite end secured on the pin 18 and the keeper plate 22 snapped into locked position.

The device is connected with a source of current supply (not shown) and then placed where rain may fall on the frangible trigger strip so that when it rains, the rain water will wet the strip permitting the same to break, thereby releasing the contacts in the switch to close the circuit to operate the signal buzzer.

As before mentioned, the improved trigger strips 13 may be used equally well in connection with any desired form of mechanical signal device for normally holding the same inoperative, as well as with switch controlled electrical signal devices.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. A rain alarm comprising a housing of insulating material, an electric switch supported within said housing including an operator rod, said housing having an opening loosely receiving said operator rod, an insulated sleeve loosely embracing said operator rod and fixed at one end to said housing, a cap of insulating material slidably mounted on the other end of said sleeve, a bearing extension fixed on said cap, spring means normally urging said cap outwardly relative to said operator rod, said switch being normally in a circuit closing position, a frangible strip having its ends fixed exteriorly of said housing, said strip extendable over said bearing extension for retaining said cap in a depressed position relative to said operator rod and for retaining said switch in a circuit open position, and means for supporting the ends of said strip in a fixed position rela-

tive to said housing, said strip including thickened end portions and said means for supporting the ends of said strip includes anchor pins carried by said housing and projecting therefrom for engaging the ends of said strip, a pair of fixed ears carried by said housing adjacent each of said pins, a locking plate pivoted on each pair of ears bearing against the ends of said strip, and a recess provided in each of said plates for engaging said anchor pins.

2. In a rain alarm including a housing and an electric switch supported within the housing having an operator rod, said housing having an opening loosely receiving said operator rod; the improvement of which comprises, a sleeve fixed to said housing and embracing said operator rod, a cap slidably carried by said sleeve, a coil spring embracing said operator rod, a flange carried by said operator rod, said spring biased between said cap and said flange for urging said cap outwardly relative to said housing, a frangible strip having its ends anchored to said housing, said strip engaging said cap to compress the coil spring and for retaining the operator rod in a depressed circuit-open position, pressure plates hinged to said housing and bearing against the ends of said strip, and anchor pins carried by said housing engaging the ends of said strip, said pressure plates shielding said anchor pins.
